UNITED STATES PATENT OFFICE

94,084

DESIGN FOR A HIGH SCHOOL BADGE OR SIMILAR ARTICLE

Henry E. Hein, New York, N. Y.

Application May 9, 1934, Serial No. 51,725

Term of patent 14 years

To all whom it may concern:

Be it known that Henry E. Hein, a citizen of the United States, and resident of 606 East 164 Street, in the county of Bronx and city of New York, State of New York, has invented a new, original, and ornamental Design for a High School Badge or Similar Article, of which the following is a specification, reference being had to the accompanying drawing, forming part thereof. The figure of the drawing is a front perspective view of the badge showing my design.

I claim:

The ornamental design for a high school badge or similar article as shown.

Signed at James Monroe High School, in the county of Bronx and State of New York, this 7 day of May A. D. 1934.

HENRY E. HEIN.
